UNITED STATES PATENT OFFICE.

OSCAR L. NOBLE, OF BOSTON, MASSACHUSETTS.

HEEL-TRIMMING TOOL.

SPECIFICATION forming part of Letters Patent No. 445,229, dated January 27, 1891.

Application filed March 13, 1886. Serial No. 195,164. (No model.)

To all whom it may concern:

Be it known that I, OSCAR L. NOBLE, of Boston, in the county of Suffolk and State of Massachusetts, have invented an Improved 5 Tool for Trimming Heels, of which the following is a specification, reference being had to the accompanying drawings, in which—

Figure 1 is a side elevation, and Fig. 2 a lengthwise section, of one of my tools. 10 My tool consists of a central stem or arbor A, adapted to be connected with or forming a part of the arbor of the machine on which my tool is to be used, two sleeves or bushings B and C, a cutter D, of any suitable construction, a guard E, and a tread-rest F, the cutter D being clamped or otherwise secured to the arbor at stem A, and one or both of the bushings being clamped by screw G or otherwise secured to the shaft A. The bushings also 15 serve as journals for the tread-rest F and guard E, in order that these parts may cease to revolve when the heel or counter is pressed against them. The tread-rest F is that described in Patent No. 308,056, of 1884, and the 20 main novelty of my tool is the combination of this tread-rest with its groove to receive the corner of the top lift with the cutter by

means of a bushing, whereby the tread-rest may remain stationary when the friction of the corner of the top lift is sufficient to arrest its revolution. I have shown a sectional cutter; but other forms may of course be used. 30

Another feature of my invention is a cutter for trimming heels provided with the guard E and rest F, both of which are loosely mounted upon the cutter and which remain stationary, or, nearly so, while the tool is in use in trimming heels; but the loosely mounted tread-rest is the main feature of my invention. 35

What I claim is—

1. The improved tool for trimming heels, consisting of the cutter D, bushings B and C, guard E, and tread-rest F, combined together substantially as and for the purpose set forth. 40

2. The improved tool for trimming heels, 45 consisting of the cutter D, bushings B and C, guard E, and tread-rest F, the tread-rest being a grooved ring loosely mounted on its bushing, substantially as and for the purpose set forth.

OSCAR L. NOBLE.
